Sybil L. Almond.

UNITED STATES PATENT OFFICE

CHARLES FRANCIS JENKINS, OF WASHINGTON, DISTRICT OF COLUMBIA, ASSIGNOR TO JENKINS LABORATORIES, OF WASHINGTON, DISTRICT OF COLUMBIA, A CORPORATION OF THE DISTRICT OF COLUMBIA

PEN-BOX INK-FEED

Application filed December 6, 1927. Serial No. 238,166.

This invention relates to apparatus for recording pen-and-ink-on-paper weather maps by radio, and has for its principal object means for applying ink to the pen-point in exactly the right amount with little loss from evaporation, and a certainty that the ink will mark the paper after considerable intervals of inaction.

With this and other objects in view, the invention consists of the novel combination of parts hereinafter described and illustrated in the drawings, and more particularly pointed out in the claims.

In the drawings Figure 1 is a side view of the pen box, and a section of the paper-carrying cylinder; Figure 2 a front view with the cylinder omitted; Figure 3 and Figure 4 top and side views of the pen. The drawings are in heroic size, i. e., very much larger than normal, for clarity.

In the drawings A represents a rotating cylinder upon which the recording paper or the base map is mounted to be moved beneath the pen-point B. The shank of the pen is gripped in the pen-arm C. The box D contains means for moving the pen-arm toward and away from the surface of the drum A. The box D also supports an ink-well E. Ink is carried from the ink-well to the pen-point by a porous string or thread F, which passes over the rim of the ink-well, through the shank of the pen, and down between the blades of the pen-point, to a position so close to the point that the capillary space therebetween keeps a constant ink supply at the pen-point. G is a screw for adjusting the separation of the pen blades to determine the fineness of the ink line of the received weather map.

As is well known, radio energy is almost infinitely small at long distances, say, 2500 to 5000 miles from the broadcast station, and it is essential, therefore, that the structure of mechanism to be moved thereby shall be built to conserve in every possible way the energy of the incoming radio signal. This is the prime object of this invention. It can well be appreciated, therefore, that the ink-well cannot be carried by the pen-arm.

But if the ink-well is fixedly held and the

pen-arm moves it is necessary that the means for carrying the ink from the well to the pen-point shall be extremely flexible so that resistance to the pen-arm movement shall be reduced to the least possible amount. The 55 porous flexible string conduit F meets this requirement better than any previously employed device.

The string is led through the hollow shank of the pen, and emerging therefrom is tucked 60 down between the blades of the pen. Therefore, the violent and irregular vibration of the pen-arm does not dislodge the ink-feed string F.

The porosity of the string protects the ink 65 from undue evaporation, the ink being carried principally inside the capillaries of the string to the point of the pen.

The soft string tucked in between the blades of the pen in no way impedes the adjustable separation of the pen-points for the extremely fine lines necessary for the map detail required.

In recording weather maps which have been received by feeble signals by radio 75 from a station many thousand miles away, a weather map upon which the navigator of a ship is to depend for the safety of passengers, ship, and cargo, the possibility of a false break in the ink lines which build up 80 the weather map must be reduced to the least possible chance.

It is extremely important, therefore, that the supply of ink to the pen shall be absolutely dependable, and that the ink shall be 85 carried to the extreme point of the pen, that is, that the pen-point shall always be wet, no matter how irregular the drain of the ink through the pen-point may be, how long or short the contact between pen and paper, 90 or how long the interval therebetween.

At the same time the ink-conduit must not impede the movement of the pen in any degree, i. e., the conduit must be extremely 95 flexible.

The string, after passing through the shank of the pen, is pointed downward between the blades of the pen, and extends slightly below the lower edge of the pen blades. The small size of the string or thread 100

and the space between the thread and the pen point is such that the surface tension of the capillaries of the thread are relieved at this point, and the capillaries "bleed", with the result that the pen-point is constantly wet.

Having enumerated the requirements of this important, but extremely delicate detail of dependable map-making by radio, 10 what I claim, is—

1. In apparatus of the class described, the combination of a bladed pen, having a sharp nib and a hollow shank; a reservoir of ink stationarily mounted with respect to said pen during the recording movement of said pen; and a porous thread extending directly from the ink reservoir through the shank of the pen, and down between the blades of the pen-point and forming a continuous flexible 15 connection between the pen and the ink reservoir and to permit free movement of the pen independently of the reservoir.

2. In apparatus of the class described, the combination of a bladed pen having an adjustably sharp nib and a hollow shank; a reservoir of ink stationarily mounted with respect to said pen during the recording movement of said pen; and a porous thread extending directly from the ink reservoir 20 through the shank of the pen, and down between the blades of the pen-point and forming a continuous flexible connection between the pen and the ink reservoir and to permit free movement of the pen independently of 25 the reservoir.

3. In apparatus of the class described, the combination of a bladed pen having an adjustably sharp nib; a reservoir of ink stationarily mounted with respect to said pen during the recording movement of said pen; a porous thread extending directly from the ink reservoir to and between the blades of the pen and maintained in engagement with the blades by the capillary feed of the ink 30 through the porous thread, the latter forming a continuous flexible connection between the pen and the ink reservoir to permit free independent movement of the pen; and means for holding the thread to prevent dislodgment from between the blades of the pen.

In testimony whereof I have affixed my signature.

CHARLES FRANCIS JENKINS.
